United States Patent

Des. 239,159

Patented Mar. 16, 1976

239,159

BOTTLE OR THE LIKE

Stanley Herbert Picker, Kingston Hill, England, assignor to Mary Quant Cosmetics Limited, Surbiton, England

Filed Sept. 24, 1973, Ser. No. 400,029

Claims priority, application Great Britain Mar. 30, 1973

Term of patent 14 years

Int. Cl. D9—01

U.S. Cl. D9—169

FIG. 1.

FIG. 2.

FIG. 3.

FIG. 4.

FIG. 5.

FIG. 1 is a top perspective view of a bottle or the like, showing my new design;

FIG. 2 is an elevational view, the side not shown being the same in appearance as the side shown;

FIG. 3 is a sectional view taken on the line 3—3 of FIG. 2;

FIG. 4 is a top plan view; and

FIG. 5 is a bottom plan view thereof.

I claim:

The ornamental design for a bottle or the like, as shown and described.
